UNITED STATES PATENT OFFICE.

JAMES A. DAY, OF KNOXVILLE, TENNESSEE, ASSIGNOR TO O. B. WISE, OF KNOXVILLE, TENNESSEE.

FEED MILL.

Application filed February 26, 1926. Serial No. 90,948.

This invention relates to feed mills and more particularly to the material contact and grinding means therefor.

Briefly stated, an important object of this invention is to provide a feed mill in which the material contact and grinding elements are in the nature of disks having their peripheries provided with teeth adapted for grinding engagement with the material, the disks being pivotally mounted so that the same are moved outwardly solely by centrifugal force and so that the same may move inwardly in the event of an excessive feed.

A further object of the invention is to provide a feed mill in which the disk-shaped material contact and grinding element are provided with a series of attaching means by which the positions of the material contact and grinding disks may be changed for the presentation of new teeth to the material.

A further object of the invention is to provide a feed mill of the character specified which is of highly simplified construction, durable in use and cheap to manufacture.

Other objects and advantages will be apparent during the course of the following description.

30 In the accompanying drawings forming a part of this application and in which like numerals are employed to designate like parts throughout the same,

Figure 1 is a vertical sectional view through a feed mill embodying the invention;

Figure 2 is a vertical transverse sectional view taken on line 2—2 of Figure 1;

Figure 3 is a plan view of one of the material contacting and grinding elements.

In the drawing wherein for the purpose of illustration is shown a preferred embodiment of the invention, the numeral 5 designates what might be said to be a stator

45 through which a drive shaft 6 extends. The drive shaft may have connection with a suitable source of power and carries a rotor consisting of a plurality of spaced substantially parallel supporting disks 7 having aligned openings for the reception of main supporting rods 8.

In carrying out the invention the main

supporting rods 8 extend through certain of the openings 9 of material contact and grinding disks 10.

Each disk may be case hardened if found desirable and is provided at the periphery thereof with a plurality of teeth 11 fashioned somewhat after saw teeth so that the same will have effective grinding engagement with the material introduced into the stator or hopper. The disk shown in Figure 3 rotates in a clockwise direction so that the sharp edges of the teeth will be engaged with the material. When the outermost teeth of the various disks are worn or partly worn the disks may be changed in their position by reason of the multiplicity of openings 9 to present new teeth for engagement with the material. This brings about the prolonged usefulness of the material contact disks without the necessity of resharpening the teeth of the same.

Particular attention is directed to the fact that the several disks 10 are independently movable and are urged outwardly into contact with the material solely by centrifugal force resulting from the rotation of the disks 7 constituting the rotor.

Since the disks 10 are urged outwardly to operative position in engagement with the material solely by centrifugal force no damage will be done in the event of an overfeed since the disks 10 will not move out quite so far as they otherwise would. When the rotor comprising the disks 7 and associated elements is not in use the disks 10 will hang loosely on the rods 8 and will at all times be ready for operation.

The parts of the mill not specifically described may be of conventional construction or an improved construction, the main feature of this invention being the construction of the material contact and grinding element.

Attention is directed to Figure 2 which illustrates that complete rotation of the material contact and grinding disks is prevented by washers 15 mounted on the shaft 6 and adapted to maintain the supporting members 7 in spaced relation to each other. By reason of this construction all the centrifugal force generated by the rotation of

the rotor is transmitted to the disks whereby more effective grinding of the material is produced.

Having thus described the invention, what is claimed is:

- 5 1. In a grinding mill having a driven shaft, a plurality of supporting elements mounted on the shaft and having aligned openings, and a rod extending through the openings, the combination of material contact and grinding disks pivotally and eccentrically mounted upon said rod and having annular series of teeth for engaging the material, each tooth having one end edge arranged substantially radially of the disk and the outer edge of each tooth extending diagonally inwardly whereby said diagonal tooth portion has both a cutting and wedging effect on the material to be ground, said disk-shaped body being provided with spaced openings adapted for selectively receiving a supporting member whereby the disk-shaped body may be adjusted with respect to said supporting member for the presentation of new teeth to the material.
- 10 2. In a mill comprising a stator, a shaft extending through the stator, a rotor mounted on the shaft and comprising a plurality of supporting members having openings, a rod extending through the openings, the combination of a plurality of disk-shaped material contact and grinding elements having the outer edges thereof provided with teeth, said disk-shaped material contact and grinding elements being provided with spaced openings to selectively receive said rod whereby the disk-shaped material contact and grinding elements may be adjusted for the presentation of new teeth to the material, and spacing members mounted upon said shaft and between said supporting

elements for spacing the same and said spacing members being positioned to engage said disks for limiting the pivotal movement of the same.

3. A material contact and grinding element for mills comprising a relatively thin disk-shaped body having the periphery thereof provided with teeth, each tooth having one end edge arranged substantially radially of the disk and the outer end of each tooth extending diagonally inwardly whereby said diagonal tooth portion has both a cutting and wedging effect on the material to be ground, said disk-shaped body being provided with spaced openings adapted for selectively receiving a supporting member whereby the disk-shaped body may be adjusted with respect to said supporting member for the presentation of new teeth to the material.

4. In a mill comprising a stator, a shaft extending through the stator, a rotor mounted on the shaft and comprising a plurality of supporting members having openings, a rod extending through the openings, the combination of a plurality of disk-shaped material contact and grinding elements having the outer edges thereof provided with teeth, said disk-shaped material contact and grinding elements being provided with spaced openings to selectively receive said rod whereby the disk-shaped material contact and grinding elements may be adjusted for the presentation of new teeth to the material, and means associated with said shaft for limiting the pivotal movement of said disks.

In testimony whereof I affix my signature.

JAMES A. DAY.
